Fig. 1

Fig. 2

Fig. 3

FIGURE 1 is a front elevational view of the loud-speaker, showing our new design, the cone-spider-voice-coil unit being omitted to show the visible interior of the spokes;

FIGURE 2 is a side elevational view thereof, the reverse side being a mirror image thereof;

FIGURE 3 is a rear elevational view;

FIGURE 4 is a front elevational view; and

FIGURE 5 is a cross sectional view thereof, taken on the line 5-5 of FIGURE 4.

The dominant features of our invention reside in the loud-speaker frame.

We claim:

The ornamental design for a loud-speaker, as shown and described.
